Des. 197,745
Patented Mar. 17, 1964

197,745

COMBINED VIEWER AND EDITOR FOR MOTION PICTURE FILM

Frank Beckman, Plainville, Conn. (141 Chapman, New
Britain, Conn.), and Gordon Florian, 300 Burr St.,
Fairfield, Conn.

Filed July 23, 1963, Ser. No. 75,941

Term of patent 14 years

(Cl. D61—1)

FIG. 1

FIG. 2

FIG. 3FIG. 4FIG. 1 is a perspective plan view of a combined viewer and editor for motion picture film, showing our design;

FIG. 2 is an enlarged front view of the device as seen normal to the plane of the device;

FIG. 3 is a side view of the device according to FIG. 1; and

FIG. 4 is a rear view of the device as seen normal to the plane of the device.

We claim:

The ornamental design for a combined viewer and editor for motion picture film, as shown.
